US00D544858S

(12) **United States Design Patent** (10) **Patent No.:** **US D544,858 S**
Lyles (45) **Date of Patent:** **** Jun. 19, 2007**

(54) **KEY BUTTON ARRANGEMENT FOR A HANDSET**

(75) Inventor: **Justin Lyles**, San Diego, CA (US)

(73) Assignee: **Nokia Corporation**, Espoo (FI)

(**) Term: **14 Years**

(21) Appl. No.: **29/218,317**

(22) Filed: **Dec. 1, 2004**

(51) **LOC (8) Cl. 14-03**

(52) **U.S. Cl. D14/247**

(58) **Field of Classification Search** D14/137, D14/138, 147-148, 247-248, 144, 218, 341-347, D14/455, 456; 379/433.01-433.13, 434; 455/575.1, 566, 556.1; D21/517, 329, 331; 345/169

See application file for complete search history.

(74) Attorney, Agent, or Firm—Banner & Witcoff, Ltd.

(57) **CLAIM**

The ornamental design for a key button arrangement for a handset, as shown and described.

DESCRIPTION

FIG. 1 is a front view of a key button arrangement for a handset showing my new design;

FIG. 2 is a perspective view thereof;

FIG. 3 is a front view of a second embodiment of the key button arrangement for a handset showing my new design; and,

FIG. 4 is a perspective view thereof.

The broken lines showing disclaimed portions of the keypad and of the handset are for illustrative purposes only and form no part of the claimed design.

1 Claim, 3 Drawing Sheets
